COMBINED CANISTER AND CABINET THEREFOR

Monte L. Levin, Roslyn Heights, N.Y., assignor to Lincoln Metal Products Corp., New York, N.Y., a corporation of New York

Filed Jan. 19, 1961, Ser. No. 63,618

Term of patent 14 years

(Cl. D44—6)

FIG. 4

FIG. 1

FIG. 5

FIG. 2

FIG. 3

FIG. 1 is a perspective view of a combined canister and cabinet therefor showing my new design;

FIG. 2 is a side elevational view;

FIG. 3 is a front elevational view;

FIG. 4 is a side elevational view with a canister in an open position; and

FIG. 5 is a side elevational view of a canister removed from the cabinet.

The essential features of the design are shown in full lines.

I claim:

The ornamental design for a combined canister and cabinet therefor, as shown and described.
